Primary Examiner — Kevin K. Rudzinski*Assistant Examiner* — Evans David Delesline(74) *Attorney, Agent, or Firm* — Bridgeway IP Law Group, PLLC; Jihun Kim; Hyun Woo Shin(57) **CLAIM**

The ornamental design for a watch strap as shown and described.

DESCRIPTION

FIG. 1 is a front perspective view of a watch strap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines throughout the drawing figures depict portions of the watch strap that form no part of the claimed design.
